UNITED STATES PATENT OFFICE

JOHN PORTER SHEARER, OF NEWARK, NEW YORK

FOLDING PAPER BOXES

Application filed January 26, 1928. Serial No. 249,721.

The present invention relates to paper box blanks and an object thereof is to provide a construction which may be fed mechanically from a folded position to a set-up position without danger of being destroyed by the feeding mechanism.

To these and other ends, the invention consists of certain parts and combinations of parts, all of which will be hereinafter described: the novel features being pointed out in the appended claim.

In the drawings:

Fig. 1 is a plan view of the blank;

Fig. 2 shows the blank in the folded condition in which it is fed by the mechanical feeding means; and

Fig. 3 is a section on the line 3—3, Fig. 2.

In the illustrated embodiment of the invention 1, 2, 3, and 4 indicate four sections 20 of a blank adapted to be folded on the scored lines 5 and connected by a flap extension 6 to provide the side walls of the box. In this instance, each of the sections 1, 2, 3, and 4 have flap extensions 1^a, 2^a, 3^a, and 4^a at opposite ends which are adapted to be folded in overlapping relation in order to form the end walls of the box. The side walls 1 and 4 are bent in overlapping relation to the side walls 2 and 3 and the flap or extension 6 is 30 adhesively secured to the side wall 1 as shown in Figs. 2 and 3 of the drawings.

The form of box so far described is well known in this art. The blank in the form shown in Figs. 2 and 3 is stacked with others 35 in a hopper and by known feeding mechanism is fed from the bottom of the hopper. In this feeding, many of these blanks are destroyed due to the fact that the end flaps 1^a, 2^a, 3^a, and 4^a, of one blank will get out 40 of alignment and interlock with the end flaps of the blank next above it so that when the feeding mechanism engages the lowest blank in the hopper the interlocking will cause a destruction of one or both of the interlocking 45 blanks and at the same time cause the stopping of the operations in the factory, thus reducing the production of the plant. A purpose of this invention is to prevent this interlocking between the end flaps of the 50 blank while they are in the feeding hopper.

This result is secured, in this instance, by providing a readily fracturable connection such as the small integral connection 7 between two adjacent end flaps preferably at each end of the blank, so that the two connected sections are held against lateral displacement. In this instance, the extensions 2^a and 3^a are connected so that when the blank is folded in the condition shown in Figs. 2 and 3, the extensions 2^a and 3^a cannot shift laterally to interlock with the extensions 1^a and 4^a of an adjacent blank.

This invention does away with considerable loss of these blanks and at the same time increases the quantity production.

What I claim as my invention and desire to secure by Letters Patent is:

As a new article of manufacture, a folded box formed of a single blank having four side sections secured together, and flaps extended from each end of each said side sections, two of said side sections having a readily fracturable connection between adjacent edges of their flaps at both ends of the sections spaced from the ends of the flaps so that the box may lie in a folded condition in a stack and provide a flat substantially uninterrupted surface on one side which will prevent its flaps interlocking with the flaps of an adjacent folded box in the stack when the box is removed from the stack in a line transversely of the side sections.

JOHN PORTER SHEARER.
